US00D841495S

(12) **United States Design Patent** (10) **Patent No.:** **US D841,495 S**
Page et al. (45) **Date of Patent:** **** Feb. 26, 2019**

(54) **FLEXIBLE WRISTBAND ACCESSORY FOR A WEARABLE FITNESS MONITOR**

(71) Applicant: **Fitbit, Inc.**, San Francisco, CA (US)

(72) Inventors: **Kevin David Page**, Morgan Hill, CA (US); **Alfred Charles Jones, II**, San Jose, CA (US); **Timothy Michael Vanderet**, San Francisco, CA (US); **Irina Igorevna Kozlovskaya**, San Francisco, CA (US); **Jonah Avram Becker**, San Francisco, CA (US); **Bernhard Wildner**, San Francisco, CA (US); **Marc Angelp Capul**, San Francisco, CA (US); **Erik Keith Askin**, San Francisco, CA (US); **Gad Amit**, San Mateo, CA (US); **Daniel Joseph Clifton**, San Francisco, CA (US)

(73) Assignee: **Fitbit, Inc.**, San Francisco, CA (US)

(**) Term: **15 Years**

(21) Appl. No.: **29/625,507**

(22) Filed: **Nov. 9, 2017**
